F. S. CARR.
SEPARABLE FASTENER.
APPLICATION FILED JULY 1, 1918.

Patented Apr. 15, 1919.

Inventor:
Fred S. Clegg.
Assignee Booth, Jamison & Murray
Harris

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,300,575.

Specification of Letters Patent. Patented Apr. 15, 1919.

Application filed July 1, 1918. Serial No. 242,698.

To all whom it may concern:

Be it known that I, FRED S. CARR, a citizen of the United States, and a resident of Newton, in the county of Middlesex, Commonwealth of Massachusetts, (whose post-office address is care of Carr Fastener Company, Cambridge, Massachusetts,) have invented an Improvement in Separable Fasteners, (C,) of which the following description, in connection with the accompanying drawings, is a specification, like characters on the drawings representing like parts.

This invention pertains to improvements in separable fasteners, and more particularly, though not exclusively, to fasteners in which a stud enters a socket and is separable therefrom by relative tipping movement of stud and socket in one direction only.

20 In the drawings, which show a preferred form of one embodiment of my invention:—

Figure 1 is a front elevation of a preferred form of socket having the stud entered therein;

25 Fig. 2 is a section on the line 2—2 of Fig. 1; and

Fig. 3 is a section on the line 3—3 of Fig. 2.

In the preferred fastener selected for 30 illustrative purposes, I have shown a stud 4 having a head 5, and a neck 6, which preferably presents, as shown, a relatively abrupt shoulder 7. Coöperating with the preferred form of stud is a socket herein 35 shown as a casing, including a front plate 8 and a back plate 9 and a yielding jaw, herein shown as a resilient element 10 held between the front plate 8 and the back plate 9. The socket is preferably apertured, 40 as shown, to receive the head of the stud 4, the bottom portion of the front plate 8 being died inwardly to provide a sloping or cam-like neck-engaging lip 11. The socket casing is shown as secured to a curtain 12 by prongs 13 extending through a clench-plate 14 in the usual manner. The stud 4 is also shown as secured to a curtain 15 by prongs 16 extending through a clench-plate 17. When the stud is entered in the 50 socket, the resilient jaw 10 springs upwardly until the stud has entered sufficiently so that the cam-like lip 11 can engage the neck of the stud, and so that the yielding jaw 10 can enter the neck of the stud behind the shoulder 7. The stud and socket

are now locked together against direct outward separation because of the engagement of the jaw 10 behind the shoulder 7.

The stud and socket cannot be separated by a lateral tipping movement because such 60 movement is prevented by the engagement of the shank portion of the stud 4 with the sides of the apertures in the plates 9 and 14. The stud and socket members cannot be separated by an outward pull on the top 65 of the socket because of the engagement of the yielding jaw 10 behind the shoulder 7 and because tipping movement in this direction is prevented by the plates 9 or 14. When, however, the bottom of the socket 70 or the bottom of the curtain is pulled outwardly, the head of the stud can ride upwardly against the sloping cam-like surface of the jaw 11, thus crowding the yielding jaw 10 upwardly until the shoulder 7 has 75 passed the jaw 11 and the shoulder 7 has been inclined sufficiently relative to the jaw 10 so that the head of the stud can unbutton from beneath the yielding jaw 10, thus permitting separation of the parts.

80 While I have shown and described a preferred form of one embodiment of my invention, it will be understood that major changes involving omission, substitution, alteration and reversal of parts, and even changes in the mode of operation, may be made without departing from the scope of my invention, which is best defined in the following claims.

Claims:

1. A stud and socket fastener comprising, in combination, a stud having a head and a neck, a socket providing a casing providing below the stud an inclined lip for engagement behind the head of said stud, and above said stud a yielding jaw for engagement behind the head of said stud.

2. A stud and socket fastener comprising, in combination, a stud having a head and a neck, a socket providing a casing providing below the stud an inclined lip for engagement behind the head of said stud, and above said stud a yielding jaw for engagement behind the head of said stud, said socket providing a three-side support for the stud rearwardly of said neck to oppose relative tipping movement of said stud and socket in three directions, while permitting relative tipping movement in a fourth direction about said yielding jaw as a fulcrum,

thereby to permit separation of said stud and socket.

3. A stud and socket fastener comprising, in combination, a stud having a head and a neck, a socket providing a casing providing below the stud an inclined lip for engagement behind the head of said stud, and above said stud a yielding jaw for engagement behind the head of said stud, said 10 socket providing a plate rearwardly of said neck having an elongated opening therein shaped to engage said stud on three sides to oppose relative tipping movement of stud and socket in three directions while permitting such tipping movement in a fourth direction.

4. A stud and socket fastener comprising, in combination, a stud providing a head and a neck, and a socket providing a front plate having a portion thereof below the stud 20 died rearwardly and providing a rearwardly sloping jaw for engagement behind said head of said stud, yielding jaw means for engagement behind said head and pressing said stud toward said sloping jaw, and 25 means opposing relative tipping of said stud and socket in three directions while permitting such movement in a fourth direction.

In testimony whereof, I have signed my name to this specification.

FRED S. CARR.
